UNITED STATES PATENT OFFICE.

WILLIAM J. MIELZINER, OF FRANKLIN SQUARE, NEW YORK, ASSIGNOR TO AMERICAN CAN COMPANY, OF NEW YORK, N. Y., A CORPORATION OF NEW JERSEY.

COLLAPSIBLE CASE.

Application filed September 14, 1925. Serial No. 56,287.

My invention relates to packing cases, and more particularly to collapsible crates of the type frequently used in shipping small articles, such as tin cans.

5 These crates are ordinarily made of slats, in order that the minimum amount of material consistent with strength of the crate may be required. They are also made collapsible so that they will occupy a minimum of space 10 in a freight car when being returned empty to the factory. In the past, the side members of the crate have been hinged together and the end members, or the top and bottom, secured in such manner as to permit one or both 15 thereof to be removed and arranged with the sides in a compact unit for shipment. In order to open the crate, one of the end members is pressed down and the fastening devices, which ordinarily are hooks rotatably attached 20 to the side members and engaging in openings in the end member, are swung out of the way, the end member then being lifted off to permit packing, or emptying of the crate. Ordinarily, four hooks have been employed, two 25 at each side of the end member, and it has been necessary to spring the end member downward and move each hook out of the way, since no provision was made for hinging said end member. Through carelessness of employees 30 in shipping and receiving rooms, effort has often been made to raise the end member without releasing all of the holding hooks, and this has resulted in bending, or mutilating the hooks which are not disengaged. In this manner, a great many crates have been damaged 35 and in many instances rendered unserviceable, and it is the purpose of my invention to provide a collapsible crate which will not be subject to the difficulties mentioned. In accordance with the invention, the construction of 40 the crate and the form of the holding hooks may remain the same as formerly, except that provision is made to permit hinging of the end member at one side, in the event that the 45 holding hooks on one side only are released, thereby preventing distortion of the hooks, or parts of the crate cooperable therewith under the circumstances above described. To this end, elongated slots are provided in the end member for the reception of the ends of the hooks and the corners of said end member are notched in such manner that when said member is raised at one side, it will hinge 50 upon the hooks at the opposite side and the

corners will clear the side members, in manner which will hereinafter more clearly appear.

Numerous other objects and advantages of the invention will be apparent as it is better understood from the following description, 60 which, taken in connection with the accompanying drawings, discloses a preferred embodiment thereof.

Referring to the drawings,

Figure 1 is a perspective view of a collapsible crate in which my invention is embodied, the same being set up and the parts arranged as for shipment;

Fig. 2 is a fragmental detail view, showing one of the holding hooks and associated parts 70 of the end and side members; and

Figs. 3 and 4 are enlarged views, showing the holding hooks and associated structure of the side and end members, Fig. 3 showing the closed position and Fig. 4 illustrating the 75 hinging action, provision for which is made by my invention.

On said drawings, illustrating the best manner in which I have thus far contemplated applying the principles of my invention, the reference characters 11, 12, 13 and 14 indicate the four side members, which are of the well-known slat construction, adjacent members being hinged together, as indicated at 15. End members 16 and 17 are provided 80 at the top and bottom and, like the side members, are formed of a series of slats secured together by other slats extending at right angles thereto. The bottom member 17 may be secured to the side members in any desired manner (not shown), either in the same manner as the top member, as will be hereinafter described, or by any form of releasable or hinge connection. The top, or upper end member 16 is adapted to be placed upon the side members and held down by means of hooks 18, of which four are shown in the present instance, two at each side of the crate. Said hooks are mounted for rotation about a vertical axis upon upper cross slats 19 of 85 the side members, being held in place by means of metal strips 21, which are secured to the inner face of the slats 19 and formed with a central channel 22 adapted to receive an elongated body portion 23 of said hooks.

Cross slats 24 at the front and back edge of the top member 16 are slotted, as indicated at 25, and have U-shaped plates 26 secured

thereto by means of screws 27, said plates being correspondingly slotted and said slots 25 being adapted to receive downturned ends 28 of the hooks 18. The lower ends of said 5 hooks are turned laterally and outward, as indicated at 29, and engage beneath the slats 19. The form of the end member 16 is such that it normally exerts an outward spring 10 tension against the hooks 18, thereby holding the latter in the slots 25 and when the crate is filled, the contents assist in holding said parts in assembled relationship. When it is desired to remove the end member, the latter may be pressed downwardly and the hooks, 15 when free, swung rearwardly, after which said end member may be removed. Prior to my invention, the slots 25 have been only slightly larger than the downturned ends of the holding hooks 18 and unless all of said 20 hooks were moved out of the way, the end member could not be moved without damage thereto, or to the hooks. In accordance with my invention, said slots are elongated (see Fig. 2), so that if the hooks at one side only 25 are released and the cover raised, the latter will have a hinging action upon the hooks at the opposite side, as clearly shown in Fig. 4.

The corners of said end member 16 are notched, as indicated at 31, so that they may 30 clear the side members in the hinging action, and it will be evident that no damage can be caused, with this construction, to the hooks or other parts from the cause earlier referred to herein.

35 It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

40 I claim:

1. A collapsible case, comprising side members hinged together and foldable to form a compact unit for shipment when the case is empty, end members, and hooks for removably fastening opposite sides of an end member to the side members, said end member having vertically extending slots in which said hooks engage and said slots being of sufficient horizontal length to permit hinging action of said end member relative to and on the hooks when one side only thereof is released.

45 2. A collapsible case, comprising side mem-

bers hinged together and foldable to form a compact unit for shipment when the case is empty, end members, and hooks for removably fastening opposite sides of an end member to the side members, said end member having slots in which said hooks engage and said slots being of sufficient length to permit hinging action of said end member relative to and on the hooks when one side only thereof is released, said end member being notched at the corners thereof to provide clearance for said hinging action.

3. A packing case, comprising a body, a removable wall member, and fastening devices comprising hooks for releasably attaching said wall member to said body at two opposite sides of the latter, said wall member having slots in which said hooks engage and said slots being lengthened transversely to the hooking parts to permit hinging action of said member relative to and on the hooks on either side of said case.

4. In a crate, the combination of a collapsible body consisting of two ends and two sides hinged one to the other, and a top member inserted between the side members and resting on the end members and having formed therein holes, and hooks mounted on vertical axes on said side members and swingable over the top member and having their vertical ends insertable into said holes.

5. In a crate, the combination of a collapsible body consisting of two ends and two sides hinged one to the other, and a top member inserted between the side members and resting on the end members and having formed therein holes, and hooks mounted on vertical axes on said side members and swingable over the top member and having their vertical ends insertable into said holes, said top member being notched at its corners so that its hinged edge may swing downward on said hooks when the other edge of the top is raised.

6. In a crate, the combination of a collapsible body consisting of two ends and two sides hinged one to the other, and a top member inserted between the side members, and having formed therein holes, and hooks mounted on vertical axes on said side members and swingable over the top member and having their vertical ends insertable into said holes, said top member holes being sufficiently extended to permit hinging of the top member relative to one side member while the hooks of said side member are still within their respective holes.

WILLIAM J. MIELZINER.
